UNITED STATES PATENT OFFICE.

W. BARNET LE VAN, OF PHILADELPHIA, PENNSYLVANIA.

STEAM-BOILER.

SPECIFICATION forming part of Letters Patent No. 367,818, dated August 9, 1887.

Application filed September 17, 1886. Serial No. 213,772. (No model.)

To all whom it may concern:

Be it known that I, W. BARNET LE VAN, of the city and county of Philadelphia, in the State of Pennsylvania, have invented certain new and useful Improvements in Steam-Boilers, of which improvements the following is a specification.

My invention more particularly relates to stationary boilers of the horizontal tubular type; and its object is to afford, in connection with structural strength and simplicity, effective and desirable means for the generation of high-pressure steam, which in operation shall present the advantages of freedom from foaming, quick steaming capacity and production of dry steam, ample releasing surface and steam room, thorough utilization of heat and combustion of the gases evolved from the fuel, and facility of removal of scale or deposits of solid matter.

To this end my improvements consist in certain novel devices and combinations, herein-after fully set forth.

In the accompanying drawings, Figure 1 is a side view in elevation of a steam-boiler, and longitudinal central section through the setting thereof, illustrating the application of my invention; Fig. 2, a view half in front elevation and half in vertical transverse section through the setting at the line *x x* of Fig. 1; Fig. 3, a view half in rear elevation and half in vertical transverse section through the setting at the line *y y* of Fig. 1; Fig. 4, a longitudinal central section through the front portion of the boiler and steam-drum and their connecting-neck, and Fig. 5 an end view of one of the supporting-brackets.

In the practice of my invention I provide a steam-boiler having a cylindrical shell composed of a series of rings or plates, 1 2 3, which are riveted one to another in telescopic form, successively and continuously increasing in diameter from the front head, 4, to the back head, 5. A series of fire-tubes, 6, extend from the front to the back head, said tubes being expanded into and beaded over the heads in the usual manner, and being preferably so arranged as to leave a clear vertical space of about three inches at the center of the boiler and a minimum equal space between the outer tubes and the shell to allow a free circulation

of water. A cylindrical steam-drum, 7, which may, if desired, be provided with a series of tubes, 8, for the passage of the gases escaping to the stack, is connected adjacent to its front end by a single neck, 9, to the front ring, 1, of the boiler-shell, its rear end being supported at a greater distance above the boiler by a bracket, 10, so that the drum shall, when the boiler is in operative position, be horizontal, 55 or substantially so, while the shell of the boiler rakes or inclines downwardly toward its rear and larger end. The drum being connected to the shell at one end only, free expansion is permitted, and tendency to strain and leakage 60 in expansion and contraction prevented.

The openings in the shells of the drum and boiler are each flanged outwardly and riveted to the neck 9, as shown in Fig. 4, thereby reducing the weakening of the shells due to the removal of metal, and a pipe, 11, near the rear end of the drum serves for the attachment of the steam-supply pipe leading to the engine, the safety-valve chest, and the pipe leading to the water or gage column and steam-gage.

The boiler is supported in and inclosed by a brick setting, in which it is fixed so that, as before stated, it shall rake or incline downwardly toward its rear end. The exact degree of inclination of the boiler is not material and 75 may be varied in the discretion of the constructor, an instance which has given satisfactory results in practice being a fall of six inches in sixteen feet. The setting is composed of side walls, 12, a rear wall, 13, and front wall, 14, 80 provided with a suitable fire-front, 15, and incloses a furnace and preliminary combustion-chamber, 16, and a supplemental combustion-chamber, 17, each of which extends upwardly 85 on the sides of the boiler to or about the level of the normal water-line thereof, the sides of the chamber 16 being outwardly inclined from their lower to their upper portions, so as to afford access for and direct the heat of the fire to the entire surface of the boiler below the 90 water-line. The products of combustion pass from the chamber 17 through a back-connection chamber, 18, into the rear ends of the tubes 6, and emerge from the front ends of the tubes into a front connection, 19, from which 95 they pass through a casing, 20, inclosing the steam-drum 7, for the purpose of superheating 100

the steam, and through the tubes of the drum, when the same are employed, into a flue, 21, provided with a suitable damper, 22, and leading to the stack 23. The boiler is supported 5 on the side walls by lugs or brackets fixed to its sides, which, for greater convenience in handling and shipment, are composed of a shell-section, 24, fixed to the boiler-shell by rivets, and a removable foot or bearing section, 25, which is bolted to the shell-section 24, so as to be readily detached therefrom when required. The fire-front 15 is provided with a suitable fire-door, 26, having a register governing the admission of air above the grate, 15 and with a door, 27, by which access is afforded to the ash-pit 28. A sight-hole, 31, covered by a plate of mica, is formed at the outer end of a passage in the front wall and fire-front, and enables the condition of the fire 20 to be observed in operation without the necessity of opening the furnace-door. A feed and blow-off pipe, 29, governed by proper valves, is led into the bottom of the boiler at or near its rear end.

25 The furnace and preliminary combustion-chamber 16 and supplemental combustion-chamber 17 are separated by a fire-bridge, 30, the top of which is placed at a suitable distance below the boiler to admit of the free passage 30 of the escaping gases, and an upwardly-inclined hearth, 32, extends from a point near the rear end of the grate 33 to the fire-bridge, the space above the hearth being a prolongation of the furnace proper and providing ample 35 room for combustion, and the inclined hearth serving to reflect the heat toward the shell of the boiler. The supplemental combustion-chamber 17 is closed at its rear end by a transverse division wall or septum, 34, extending 40 from its bottom to its top, and having a series of perforations or passages, 35, for the escape of the gases of combustion in that portion of its surface below the shell of the boiler, the gases being downwardly deflected by the closed 45 upper portion of the wall, and having no avenue to the stack except through its lower perforations.

In operation the heat of the fire is applied

to the entire exterior of the wet surface of the boiler by the upward extension of the 50 chambers 16 and 17 to or about the water-level, and the division wall or septum 34, which deflects the gases to the lower portion of the chamber 17, becoming highly heated, correspondingly promotes combustion. The gases 55 evolved from the fuel are effectually mingled with a proper supply of oxygen and consumed before entering the tubes, and the heat of the waste gases is desirably utilized in superheating the steam in the drum. The telescopic 60 form and inclination of the boiler-shell allows all scale and solid matter deposited by the feed-water to pass freely to the rear end of the boiler, at which the blow-off pipe is located, and from which the deposit may be readily 65 removed by blowing off from time to time, as required. The inclination of the boiler-shell further provides a larger amount of impinging surface for the action of the heated 70 gases, and the angular position of the front head admits of an easier release of the gases from the tubes to the exit-flue leading to the stack.

I claim as my invention and desire to secure by Letters Patent—

1. The combination of a steam-boiler and a separate steam-drum, each having an outwardly-flanged opening in its shell and an outwardly-flanged connecting-neck riveted at its ends to the flanges of said openings, substantially as set forth.

2. The combination of a tubular steam-boiler, a setting inclosing a furnace and combustion-chamber below the boiler, said furnace and combustion-chamber each extending upwardly to or about the line of normal water-level, a transverse bridge-wall interposed between the furnace and combustion-chamber below the boiler-shell, and a transverse perforated division wall or septum closing the opposite end of the combustion-chamber, substantially as set forth.

W. BARNET LE VAN.
